UNITED STATES PATENT OFFICE.

SCHUYLER HAMILTON, JR., OF NEW YORK, N. Y.

PROCESS OF BURNING BRICK.

SPECIFICATION forming part of Letters Patent No. 340,780, dated April 27, 1886.

Application filed December 10, 1885. Serial No. 185,262. (No specimens.)

To all whom it may concern:

Be it known that I, SCHUYLER HAMILTON, Jr., a citizen of the United States, residing at New York, in the county of New York and State of New York, have invented certain new and useful Improvements in Processes of Burning Brick; and I do declare the following to be a full, clear, and exact description of the invention, such as will enable others skilled in the art to which it appertains to make and use the same.

The invention relates to the manufacture of brick; and it consists in a novel process or method of burning the same by first subjecting them to a coke-fire, and then continuing the heat by adding to the fire a quantity of coke and coal mixed in proper proportions.

The object of the invention is to render the burning of the brick more effectual and less expensive—more effectual, because by my process fewer defective brick will be found in each “burn” than heretofore, and less expensive for the reason that the cost of production is greatly reduced and the quality of the brick improved.

In carrying the invention into effect, the fire under the grate-bars of the kiln is started in the customary manner and coke applied, and after the coke-fire has burned a suitable length of time the heat is continued by adding a mixture of coke and coal, under which latter condition the burning of the brick is completed.

The proportions of the coke and coal may be varied to some extent without material prejudice to the result; but I recommend that they be used in equal parts—that is, that the mixture be composed one-half of coke and the other half of coal.

By means of my invention herein described the brick may be more evenly burned than by any process of burning brick now in use; and but a very slight percentage of “salmon” or light colored and other defective and inferior brick will be found in each burn when it is employed.

When my process is made use of, the brick may be burned in the ordinary clamp-frame kiln instead of in the permanently-built kilns required for burning brick with a wood-fire,

and the length of time required for each burn when my process is followed is about thirty-six hours less than that necessary when a wood-fire is made use of, and in addition the wood-fire is much the more expensive of the two. 55 When coal is made use of alone for the fire, the spaces between the brick rapidly become clogged with soot, owing to the nature of the coal and the dampness of the brick, and the burning and uniformity of the brick is greatly 60 impaired.

I have used both anthracite and bituminous coal with the coke in the practice of my invention; but I recommend, on account of its marked advantages, the bituminous coal. The coke at the starting of the fire evenly and effectually prepares the brick without injury for the subsequent action of the long gaseous flames which I am able to secure with the mixture of coal and coke, and the effect of which 70 is that the brick in all parts of the kiln will be of uniform color and hardness. There are always, of course, some light-colored and defective brick in each burn, no matter what process is followed; but I have demonstrated 75 in practical and commercial tests that when the process herein claimed is made use of the proportion of light-colored and defective in each burn is very insignificant as compared with the results of any other known method 80 or means of burning brick.

Among the main advantages derived from the use of the invention are the saving of expense and time, the production of more uniformly colored and hardened brick, and the 85 material lessening of the quantity of light-colored and defective brick in each burn.

What I claim as my invention, and desire to secure by Letters Patent, is—

The method hereinbefore described of burning brick, which consists in first subjecting them to a coke-fire and then continuing the heat and completing the burning of the brick by adding to the fire coke and coal mixed.

In testimony whereof I affix my signature in 95 presence of two witnesses.

SCHUYLER HAMILTON, JR.
